[57] CLAIM

The ornamental design for a combined temperature and respiration sensing probe, substantially as shown.

DESCRIPTION

FIG. 1 is a left front perspective view of a combined temperature and respiration sensing probe showing our new design;

FIG. 2 is a left rear perspective view thereof;

FIG. 3 is a top plan view thereof;

FIG. 4 is a left side elevational view thereof, the right side being a mirror image thereof;

FIG. 5 is a bottom plan view thereof;

FIG. 6 is a rear end elevational view thereof; and

FIG. 7 is a front end elevational view thereof.
